UNITED STATES PATENT OFFICE.

LOUIS B. HASBROUCK, OF ELMIRA, NEW YORK, ASSIGNOR TO ECLIPSE TEXTILE SERVICES, INC., OF ELMIRA, NEW YORK, A CORPORATION OF NEW YORK.

SLUB CATCHER.

Application filed July 30, 1924. Serial No. 729,052.

- This invention relates to slub catchers and aims to provide a simple device for eliminating slubs, bunches and enlargements from worsted and other yarns.
- 5 While a device embodying the invention possesses peculiar advantages when used in connection with worsted yarns, such a device is none the less well adapted for general use as a slub catcher.
- 10 Worsted and other soft, long-fiber yarns frequently contain bunches and other imperfections which, while soft and often only slightly thicker than the normal thickness of the yarn, render the fabrics produced 15 from the yarns imperfect and cause injury to the knitting machines unless they are broken out of the yarn before it is used.
- A slub catcher of the type used on cotton yarn, consisting usually of a pair of transverse blades providing edges between which the yarn is drawn, is incapable of removing such bunches and imperfections from worsted yarn. This arises from the fact that such bunches are not caught on the opposed edges of the blades unless the blades are placed so close together that they scrape and injure the yarn. A further difficulty in attempting to use such slub catchers on worsted yarns arises from the fact that such 25 yarns are frequently knotted, and that, if the blades of the slub catcher are set closely enough together to catch even relatively large slubs, the yarn is broken whenever a knot encounters the blades. This is a serious disadvantage, since it necessitates retying all the knots in the yarn.
- A device constructed in accordance with my invention serves to break out all bunches and enlargements in worsted yarns and at 30 the same time to permit free passage of small knots in the yarn. Such a device provides two opposed surfaces between which the yarn is drawn. The surfaces are separated by a distance sufficient to permit free 35 passage of the yarn. Whenever a bunch or enlargement on the yarn enters between the surfaces, the enlargement is confined between the surfaces and brought into frictional contact with them. The friction thus produced between the enlargement and one of the surfaces is utilized to cause an approaching movement of the surfaces, so that they pinch and break the yarn.
- In a device embodying the invention in a 40 form which I consider most desirable, one of
- the opposed surfaces is provided by a conical member mounted on a worm which causes it to move lengthwise when it is rotated by frictional contact with an enlargement on the yarn. This lengthwise movement of the conical member causes its conical surface to approach a fixed surface at the opposite side of the yarn so that the yarn is pinched between the two surfaces and broken.
- 45 Other features and advantages of the invention are hereinafter set forth in connection with a detailed description of a complete slub catching and tensioning apparatus adapted for use in conjunction with a 50 spooling, winding or other machine, and consisting of a number of units mounted side by side on a supporting bar provided by such a machine, and common adjusting mechanism for the units. Such an apparatus, embodying the invention, is shown in the accompanying drawings, in which:
- 55 Fig. 1 is a plan view of the apparatus;
- 60 Fig. 2 is a front elevation of the apparatus with part of the adjusting mechanism 65 sectioned on the line 2—2 of Fig. 1;
- 65 Fig. 3 is a side elevation of one of the units showing the supporting rod and adjusting rod in transverse section;
- 70 Fig. 4 is a fragmentary elevation sectioned 75 on the line 4—4 of Fig. 1, and showing parts of the slub catcher of one of the units in their normal position;
- 75 Fig. 5 is a view similar to Fig. 4 showing the movable element of the slub catcher 80 positioned to pinch the yarn;
- 80 Fig. 6 is a plan view of the tension device 85 of one of the units with supporting parts sectioned on the line 6—6 of Fig. 3;
- 85 Fig. 7 is a partial side elevation of one of 90 the units, looking in the direction opposite from Fig. 3, showing the adjustable mounting of the tension device of the unit;
- 90 Fig. 8 is a partial side view of one of the units, looking in the same direction as Fig. 100 3, showing an adjustment of the tension device different from that shown in Fig. 3.
- 100 The apparatus shown in the drawings includes a plurality of units 10, 10' mounted side by side on a horizontal rod 11 which 105 may be part of a spooling or winding machine in conjunction with which the units are to be used. Although only two units are shown in the drawings, it will be understood 110 that the number actually used is equal to the

number of yarns which are simultaneously drawn into the spooling or winding machine. The supporting frame of each unit includes a horizontal plate 12, secured to the 5 rod 11 by means of a clamp 13, and a vertical plate 14, which may be formed integral with the plate 12, as shown. To the upper end of the vertical plate 14 of each unit is secured the supporting plate 20 of 10 a slub catcher, while at a lower point on each plate 14 is secured the supporting plate 60 of a tension device which serves to keep the yarn under tension in its passage through the slub catcher.

15 As the slub catchers of the different units are identical, a description of one of them will suffice. The slub catcher mounted on the plate 14 includes, in addition to its supporting plate 20, a fixed element 21, a movable element 22 and two thread guides 23, 24 for guiding the yarn between the fixed and movable elements. The fixed and movable elements 21, 22 are mounted on a horizontal extension 25 of a supporting plate 20 located at the middle of the lower end of that plate. The fixed element 21 consists of a bent strip of metal having at its lower end a horizontal portion 26, which is secured to the lower side of the support 25 20 by means of screws. The mounting of the movable element 22 includes a cylindrical stud 27 journaled in a hole 28 in the support 25 and in a hole 29 in a horizontal flange 30 extending from the upper edge of the 35 supporting plate 20, and a worm 31 extending from the upper end of the stud 27 with its axis at one side of the axis of the stud. The journaling of the stud 27 and the eccentric arrangement of the worm 31 are for the 40 purpose of adjustment as hereinafter explained, and during the operation of the slub catcher these parts are held against rotation. The worm 31 contains a helical groove 32 having a steep pitch. A horizontal stop flange 33 is located at the lower 45 end of the worm 31. The movable element 22 has a central hole, by means of which it is journaled on the worm 31, and is provided with a pin 35, whose inner end projects into the helical groove 32. The pitch of the groove in the worm 31 is so steep that the element 22 can slide down the worm under force of gravity, so that it normally rests with its lower surface on the stop 33.

50 The movable element 22 has the general shape of a cone and is mounted with its smaller end uppermost. It has a yarn-engaging surface 36, which is conical, the word "conical" being used herein in a generic sense 55 to indicate any tapered surface of revolution. The surface 36 is most desirably knurled or otherwise roughened. The fixed element or strip 21 has its upper portion inclined inwardly toward the axis of the cone 60 65 22 to provide a flat yarn engaging surface 38,

which is opposed to the yarn-engaging surface 36 of the cone, being parallel to a plane tangential to the surface 36, and is spaced from the surface 36 when the cone rests on the stop 33. The edges 37 of the strip 21 70 at the sides of its surface 38 are rounded so that they cannot scrape or tear the yarn. By means of the adjusting mechanism hereinafter described, the yarn-engaging surfaces 36, 38 are set at a distance from each other which is slightly more than the diameter of the yarn to be operated upon.

In the operation of the slub catcher, a 75 yarn A, placed under tension by means hereinafter described, is drawn, by winding or 80 spooling mechanism not shown in the drawings, over the thread guide 23, between engaging surfaces 36 and 38, and over the thread guide 24. These guides are so positioned that the yarn is normally just out of 85 contact with the roughened surface 36 and has either no contact or a very light contact with the surface 38. The travel of the yarn is, therefore, not retarded by its passage between these surfaces. 90

Whenever a slub or a slight enlargement on the yarn is drawn between the surfaces 36 and 38, it is confined between these surfaces, so that it comes into frictional contact with the roughened surface 36. As the yarn 95 continues to be drawn forward, the frictional engagement between the enlargement on the yarn and the roughened surface 36 causes the portion of the surface 36 in contact with the yarn to move in the direction 100 of the travel of the yarn. This turns the cone 22 in an anti-clockwise direction looking from the top. As soon as the cone begins to turn, it rises on the worm 31, bringing its surface 36 closer to the surface 105 38 of the fixed element 21, so that the yarn is pinched between these surfaces and broken. The presence of the enlargement on the yarn is thus made evident to the operator, who may break out the portion of the 110 yarn containing the enlargement and re-tie the yarn. In this way, all slubs and enlargements, including those whose thickness is only slightly greater than that of the yarn, are eliminated. 115

When small knots, whose presence on the 120 yarn is not objectionable, are drawn between the surfaces 36 and 38, they do not turn the cone 22 sufficiently to cause it to pinch the yarn. Such knots, therefore, pass through the slub catcher without breaking the yarn.

In order to adapt the device for operation on yarns of different sizes, adjusting means are provided for varying the distance between the surface 28 of the fixed element 21 and the surface 36 of the cone 22 when the cone is in its normal position resting upon the stop 33. The adjusting mechanism illustrated provides for the simultaneous adjustment of the slub catchers of all the units 125 130

which are mounted side by side upon the supporting bar 11.

The adjusting mechanism includes a vertical bracket 40 fixed to one end of the supporting bar 11. Near the top of this bracket is fastened a bearing piece 41, in which is journaled an adjusting nut 42. A screw 43 threaded in a transverse hole in the bearing piece 41 has its inner end 33 in engagement with a circumferential groove 45 formed in the outer surface of the nut 42. A longitudinally movable adjusting rod 46 has one of its ends screwed into nut 42, and extends through aligned holes 47 in the supporting plates 20 of the slab catchers of the different units. A pin 48 fixed in the rod 46 and projecting through a longitudinal groove 49 in a box 50 mounted on one side of the bearing piece 41 prevents the rod 46 from rotating about its axis. Blocks 51 are adjustably secured on the rod 46 and positioned near each unit. Each of these blocks carries a pin 52, which is engaged by a hook 53 at the outer end of an arm 54 projecting radially from the stud 27 of the slab catcher of each unit.

Simultaneous adjustment of all the slab catchers may be made by turning the nut 42, which causes a longitudinal movement of the rod 46. The rod, acting through the arms 54, turns the stud 27 of each unit, moving each worm 31 and the cone 22 mounted thereon about the axis of the stud 27, so as to bring it either nearer to the fixed element 21 or further therefrom. A very fine adjustment may be obtained by means of the mechanism described, both because of the threaded connection between the nut 42 and the rod 46 and because the arms 54 are much greater in length than the distance between the axis of each stud 27 and the axis of the worm 31 mounted thereon. The latter fact, which results in making the lateral movements of the worms of the slab catchers very much less than the corresponding longitudinal movements of the rod 46, makes it possible to provide an enlarged scale 55 on the box 50 to cooperate with the pin 48 on the rod 46 in indicating the gage of yarn for which the apparatus is adjusted.

In order that the apparatus may be used to operate on yarns of different sizes, it is necessary that the tension placed on the yarns drawn through the slab catchers be adjustable. For this purpose, each unit is provided with an adjustable tension device, which, in itself, forms a part of my invention.

The tension device of each unit includes, in addition to its supporting plate 60, a horizontal bed 61 having a vertical arm 62 attached to the plate 60 by means of a horizontal pivot 63, a rotatable tension disc 64 resting on the bed 61, and a tension bar 65 carried by a projection 66 extending laterally from the arm 62. The bed 61 contains slots 61^a to permit the escape of any dirt removed

from the yarn as it passes between the bed and the tension disc.

To facilitate the threading of the tension device, the bed 61 is provided with ears 67 which guide the yarn into a slot 69 extending under the tension disc 64, and the tension rod 65 is provided with a bent end portion 70, which extends over the tension disc and beyond the slot 69. In threading the tension device, the yarn is dropped between the two ears 67, drawn against the extension 70 until it slips under the tension rod 65, and is then passed over the thread guides 23, 24.

The lower surface of the tension rod 65 lies in substantially the same plane as the upper surface of the bed 61, so that, after the tension device is threaded, the yarn is drawn evenly across the upper surface of the bed 61, and then around tension rod 65.

The tension placed on the yarn is adjusted by varying the angle through which the yarn changes its direction in passing across the tension rod 65. To reduce the tension, the arm 62 is turned about the pivot 63 so as to increase the angle B between the reach of the yarn traveling toward the tension rod 65 and the reach of the yarn traveling away from this rod. (See Figs. 3 and 8). The arm 62 may be held in any adjusted position by means of a screw 72 passing through a slot 73 in the arm and entering the supporting plate 60. It should be noted that such adjustment of the tension does not interfere with the alignment between the upper surface of the plate 61 and the lower surface of the tension bar 65.

In using the apparatus which has been described, the slab catchers are first adjusted by means of the nut 42 to the proper position for a yarn of the gage to be used. The tension device of each unit is adjusted to provide the tension desired on such a yarn. The units are then threaded in the manner hereinbefore described, and as the yarns are drawn through the units, slubs, bunches and enlargements on the yarns are broken out automatically by the operation of the movable elements 22.

It should be noted that in cases where it is desired to break out only those slubs and enlargements which exceed a predetermined thickness, this result may be accomplished by so adjusting the slab catchers that only enlargements exceeding this thickness are pressed into frictional contact with the surfaces 36 of the cones 22.

I wish it understood that many changes may be made in the specific embodiment illustrated and described without departing from my invention, the scope of which is indicated in the claims which follow.

What I claim is:—

1. A device for eliminating slubs, bunches and enlargements from a traveling yarn, comprising a fixed element and a movable

- element having normally spaced opposed surfaces between which the yarn is drawn, the movable element being so mounted that movement of its said surface in the direction of the travel of the yarn, under the friction thereon of an enlarged portion of the yarn, causes it to move bodily towards the fixed element in a direction perpendicular to the yarn.
10. 2. A device for eliminating slubs, bunches and enlargements from a traveling yarn, comprising a turnable element having a curved surface, a fixed element having a surface opposed to said curved surface, and means for guiding the traveling yarn between said surfaces in a direction transverse to the axis of the turnable element, the turnable element being so mounted that a turning thereof, caused by the frictional engagement with its curved surface of an enlarged portion of the yarn, causes it to move axially toward the fixed member.
15. 3. A device for eliminating slubs, bunches and enlargements from a traveling yarn, comprising a conical element, a worm mounting for said conical element which constrains it to move axially when turned about its axis, a fixed element having a surface opposed to the conical surface of said conical element, means for guiding the traveling yarn between said conical surface and the surface of the fixed element in a direction transverse to the axis of the conical element, and means for normally positioning the conical element with its conical surface spaced from the surface of the fixed element by a distance approximately equal to the diameter of the yarn.
20. 4. A device for eliminating slubs, bunches and enlargements from a traveling yarn, comprising a fixed worm, a cone mounted thereon and having a roughened conical surface, a fixed element having a surface opposed to the roughened surface of the cone, means for guiding a traveling yarn between said surfaces in a direction transverse to the axis of the cone, and means for normally positioning the cone with its roughened surface just out of contact with the yarn.
25. 5. A device for eliminating slubs, bunches and enlargements from a traveling yarn, comprising a fixed worm, a cone mounted thereon, a fixed element having a surface inclined toward the axis of the cone and opposed to the conical surface thereof, means for guiding a traveling yarn between said surfaces in a direction transverse to the axis of the cone, said cone being yieldably urged to turn in such direction that its conical surface is moved away from the surface of the fixed element, and means for arresting such turning of the cone when its conical surface is spaced from the surface of the fixed element by a distance approximately equal to the diameter of the yarn.
30. 6. A device for eliminating slubs, bunches and enlargements from a traveling yarn, comprising a fixed worm having a vertical axis, a cone mounted on said worm with its smaller end upwards, the pitch of the worm being such that the cone is urged to rotate and descend along the worm under the force of gravity, a stop for limiting such descent of the cone, a fixed element having a surface inclined toward the axis of the cone, opposed to the conical surface thereof, and spaced therefrom when the cone rests against said stop, and means for guiding a traveling yarn between said surfaces in a line transverse to the axis of the cone.
35. 7. A device for eliminating slubs, bunches and enlargements from a traveling yarn, comprising a rotatable stud mounted with its axis vertical, a worm mounted on the upper end of said stud with its axis vertical and spaced laterally from the axis of the stud, a cone mounted on said worm with its smaller end upwards, a fixed element having a surface inclined toward the axis of the cone, and means for turning the stud about its axis to adjust the distance between the cone and the fixed element and for retaining the stud in adjusted position.
40. 8. A device for eliminating slubs, bunches, and enlargements from a traveling yarn, comprising a conical element, a worm mounting for said conical element which constrains it to move axially when turned about its axis, a fixed element having a surface opposed to the conical surface of said conical element, and means for guiding a traveling yarn between said conical surface and the surface of the fixed element in a direction transverse to the axis of the conical element.
45. 9. A device for eliminating slubs, bunches, and enlargements from a traveling yarn, comprising a worm, a cone mounted thereon, a co-operating element presenting a surface opposed to the conical surface of the cone, means for guiding a traveling yarn between said opposed surfaces in a direction transverse to the axis of the cone, the cone being yieldably urged to turn in such direction as to separate said opposed surfaces, a stop for limiting such turning of the cone, and means for varying the relative position of the axis of the worm and the said co-operating element to adjust the distance between said opposed surfaces when the cone rests against the stop.
50. In testimony whereof I have hereunto set my hand.

LOUIS B. HASBROUCK.
